UNITED STATES PATENT OFFICE

SYLVESTER E. MOORE, OF YUMA, ARIZONA

TURNTABLE

Application filed February 12, 1930. Serial No. 427,888.

My invention has reference to turn-tables, and it is a purpose of my invention to provide a turn-table primarily designed, although not necessarily, for use in connection with the 5 automobile driveways of private residences and preferably adjacent the garage, in order that an automobile may be driven onto the turn-table and the latter then manually rotated to reverse the position of the automobile 10 so that it can be driven from the driveway front end foremost, and not backed out as is the present method. In this manner I eliminate, or at least reduce to a minimum the possibility of personal injury to predestrains 15 traversing a pavement at the end of the driveway, or any accident as a result of the driver's failure to observe the boundaries of the driveway as well as the traffic traversing the street intersecting the driveway.

20 Structurally my invention is characterized by its simplicity, low cost of manufacture, easy mode of assembly and disassembly, ready substitution of any of its parts should they become worn or broken; and primarily a turn-table in which the platform thereof is so freely supported for rotation that when an automobile is thereon, it can be easily rotated by a single person and without the necessity of employing mechanical power.

30 I will describe only one form of turn-table embodying my invention, and will then point out the novel features thereof in claims.

In the accompanying drawings:

Fig. 1 is a view showing in top plan one 35 form of turn-table embodying my invention with a portion of the platform thereof broken away to reveal the construction of the platform frame.

Fig. 2 is a vertical sectional view taken on 40 the line 2—2 of Fig. 1.

Fig. 3 is an enlarged vertical sectional view taken on the line 3—3 of Fig. 1.

Fig. 4 is a detail view on a reduced scale showing the platform in bottom plan.

45 Fig. 5 is a view on a reduced scale showing in plan the turn-table embodying my invention in applied position within the driveway of a private garage.

50 In carrying out my invention, a driveway D leading to a garage G is constructed with a

pocket P of such diameter as to receive the parts of the turn-table embodying my invention, and in such manner that the turn-table is flush with the surface of the driveway to permit the automobile to be driven 55 onto or off of the turn-table incident to entering or leaving the garage. Centrally within the pocket P is a pier 15 formed of concrete or the like and having embedded therein a post 16, the latter having at its lower end a 60 disk shaped head 17 which, when embedded in the concrete serves to hold the post in true vertical position. The upper end of the post projects above the pier 15 so that it may be utilized to form an axis upon and about which 65 the platform of the turn-table is supported for rotation.

As best illustrated in Fig. 2, the platform of the turn-table is made up of a frame F for supporting a top T. The top T may be 70 of any suitable construction but in the present instance it is formed of wooden boards secured to each other at the marginal edge of the top by means of straps 18 of iron or any other suitable metal, as best illustrated 75 in Fig. 4. Other straps 18^a are employed to secure the boards to each other at points spaced from the marginal edges. The frame F comprises a plurality of subsidiary frames which serve to effectively support the top T 80 and in such manner that the weight of an automobile when on the top will be distributed uniformly over the entire area of the platform in order that the platform may be 85 easily and manually rotated.

The frame is constructed with the purpose in mind of permitting ready substitution of its parts in the case of repair, and parts which can be easily made. To this end the frame is made up of a plurality of subsidiary frames detachably secured to each other so that in the event of repair, any one frame may be detached from the other and a new frame substituted. These two subsidiary frames, designated at 19, are made 90 from lengths of steel straps bent in the form of a U, with their intermediate portions in confronting relation to each other, and their parallel portions projecting to the marginal 95 edge of the top T. The other two subsidiary 100

frames, designated at 20, are likewise made of straps of steel or other suitable material, and constructed so as to form linear portions 20^a arranged in confronting relation to each other and divergent end portions 20^b which extend to the marginal edges of the top T. The linear portions 20^a are interposed between the medial portions of the subsidiary frames 19, and they are secured 5 to each other and in this relation by means of two pairs of U bolts 21 extending through plates 22 with nuts 23 on the ends of the bolts for securing the plates to the bolts and the bolts in encompassing relation to the adjacent parts 10 of the subsidiary frames. Between the two pairs of U bolts 21 are arranged two plates 24 and 25 held in superimposed relation to each other at the lower side of the frames by means of two U bolts 26. Although I 15 have shown and described only two subsidiary frames 20, it will be understood that any number of such frames may be employed depending upon the load to be supported on the platform. For example, two subsidiary 20 frames may be sufficient for an automobile of light weight, whereas, for heavy automobiles, four or more of such frames are employed.

As best shown in Fig. 2, the lower plate 25 is provided with an opening, the walls of 25 which are outstruck to provide a collar 27, and the internal diameter of this collar is such that it receives the upper end of the post 16 and in such manner that it bears 30 against the under side of the upper plate 24. Thus, a bearing is provided for the post, with 35 the collar 27 maintaining the platform frame against edgewise displacement in respect to the post.

Lubrication and reduction of friction between the frame plate and post may be accomplished by the provision of a tube 28 extended downwardly through the plates 24 so that its lower end is disposed between the plates 24 and 25 and adjacent the post 16 so 40 that a suitable lubricant may be supplied through the tube and into the bearing.

The radiating arms of the subsidiary frames carry at their outer ends brackets 29 in which casters or rollers 30 are journaled, 45 these rollers adapted to have rolling contact with a track. This track is disposed within the pocket P and upon a suitable concrete base. The track is made up of one or more angle bars 31 arranged in circular form to 50 provide a circular track having the diameter of that defined by the arrangement of the rollers 30. The track may be partly embedded in the concrete base in the manner illustrated in Fig. 2, and so that the vertical webs 55 of the angle bars which constitute the track proper are effectively braced against horizontal movement or bending. Upon the upper edge of the vertical part of the track, the rollers 30 are adapted to ride and to support 60 the platform against any lateral movement.

in the event that the load imposed thereupon is not evenly distributed over the platform.

In practice, the platform of the turn-table is freely rotatable upon the post, and with the turn-table positioned in the driveway and in respect to the garage, as illustrated in Fig. 5, it will be clear that an automobile entering or leaving the garage can pass onto the platform, so that by rotating the latter, the automobile may be positioned with its front end foremost so that it can be driven in this position out of the driveway.

Although I have herein shown and described only one form of turn-table embodying my invention, it is to be understood that various changes and modifications may be made herein without departing from the spirit of the invention and the spirit and scope of the appended claims.

I claim:

1. A turn-table comprising a revolvable platform, a support therefor including a center pier, a post partly embedded in the pier, a circular track comprising an angle bar positioned so that one of its webs is 50 standing to form a relatively narrow and single track, rollers carried by the platform, and a central bearing on the platform in which the central post is journaled.

2. A turn-table comprising a revolvable platform, a support therefor including a center pier, a post partly embedded in the pier, a pair of superimposed plates carried by the platform with one of the plates provided with an opening in which said post is received 100 so as to bear against the other plate, a circular track, and rollers on the platform bearing on the track.

3. A turn-table comprising a supporting structure including a circular track, an upstanding post centrally within the area defined by the track, and a platform including a frame composed of a plurality of bars secured to each other, rollers carried by the bars to contact with said track, and means secured to the bars and receiving and engaging the post to provide a bearing therefor about which the platform is adapted to rotate.

4. A turn-table comprising a supporting structure including a circular track, a pier, a post embedded in and projecting from the pier, and a platform including a top and a frame composed of a plurality of bars bent to form a plurality of subsidiary frames, means for securing the subsidiary frames to each other, rollers carried by the frames so as to have contact with said track, and a pair of plates secured to the subsidiary frames, said plates being superimposed with the lower plate provided with an opening in which said post is received so as to have contact with the upper plate.

5. A turn-table as embodied in claim 4 wherein a tube extends through said top and

between said plates to permit the supply of lubricant to said post.

6. In a turn-table, a platform comprising a top, and a supporting structure therefor including a pair of U-shaped frames reversely arranged so that their intermediate portions are confronting, another pair of frames having intermediate linear portions contacting with each other and interposed between the intermediate portions of the U-shaped frames, and end portions arranged in divergent relation to each other, and means for securing the intermediate portions of all of the frames to each other.

15 7. In a turn-table, a platform comprising a top, and a supporting structure therefor including a pair of U-shaped frames reversely arranged so that their intermediate portions are confronting, another pair of frames having intermediate linear portions contacting with each other and interposed between the intermediate portions of the U-shaped frames, and end portions arranged in divergent relation to each other, and means for securing the intermediate portions of all of the frames to each other, and a pair of superimposed plates secured to the under side of the intermediate portions of the frames, with the lower plate having a collared opening therein.

30 8. In a turn-table as embodied in claim 6 wherein the top comprises a plurality of boards, and strap irons secured to and spanning the under sides of the boards adjacent the marginal edge of the top.
